HEADREST

Gerard Angelot, Youngstown, Ohio

Application January 18, 1946, Serial No. 642,013

3 Claims. (Cl. 155—173)

1

This invention relates generally to the class of furniture and pertains particularly to an improved attachment for a porch or lawn swing.

In the usual type of porch or lawn swing wherein there is provided a relatively long seat suspended upon a frame to permit the seat to be oscillated backwardly and forwardly, the back rest against which the back cushions are placed is of such height that an occupant of the swing has nothing against which to rest his head if he desires to recline or lean back since the height on the back rest and of the back cushions comes approximately only to the tops of the shoulders.

The present invention has for its principal object to provide an attachment for the back rest of a swing of this type which provides an extension above the back rest and back rest cushions, against which an extra cushion may be placed, so that a rest is provided against which the head may be placed.

Another object of the invention is to provide a back rest attachment which is designed to be easily and quickly mounted upon the frame of the back rest so as not to interfere with the customary placement of the back rest cushions against the rest and to provide an upwardly extending portion against which an extra cushion may be placed, the extra cushion being permitted to rest upon the top of the usual back rest cushion of the swing structure.

A still further object of the invention is to provide an attachment of the character stated which may be conveniently folded when it is not in use, so that it may be stored away or kept in some small space where it will be inconspicuous and out of the way.

The invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from the salient features of the invention as expressed in the appended claims.

In the drawing:

Figure 1 is a view in elevation of a portion of the back rest frame of a porch swing, together with a portion of the bottom or seat frame and showing in elevation a back rest attachment constructed in accordance with the present invention and set up for use;

Figure 2 is a detail section taken substantially on the line 2—2 of Figure 1;

Figure 3 is a view in elevation of the back rest attachment folded for storage.

Referring now more particularly to the drawing, the numeral 10 generally designates a por-

2

tion of the usual angle iron back rail of a porch swing's bottom frame.

The numeral 11 generally designates a portion of the back rest frame of a porch or lawn swing which is normally made up of a top rail 12, customarily of angle iron material, and the vertically spaced parallel flexible slats or bands 13 which are formed from relatively thin ribbonlike steel material so as to have a slight spring. Since the construction of a lawn or porch swing back rest frame is well known, it is thought that a more detailed showing of the structure is unnecessary for the proper illustration of the manner of using the present invention.

The back rest frame 11 is usually mounted upon the bottom spring frame 10 in such a manner that it may be adjusted from a vertical position to a rearwardly inclined or reclining position and the usual seat and back cushions, not shown, are placed upon the spring frame 10, and against the back rest frame so that the tops of the back rest cushions come only slightly above the top rail 12 of the back rest.

In accordance with the present invention there is provided a relatively long collapsible frame unit constituting a vertical extension of a portion of the back rest frame, which unit is generally designated 14.

The back rest unit attachment comprises a central flat rigid bar 15 with which is associated the pair of side bars 16 which are of the same length as the center bar 15 and are flat and relatively rigid.

Adjacent to the upper ends of the bars 15 and 16, the side bars are pivotally joined to the center bar by the flat coupling links 17. These links are arranged in pairs transversely of the center bar 15 and the adjacent ends of each pair of links are pivotally attached to the center bar by suitable pivot bolts or rivets 18 while the outer ends of the links of each pair are pivotally attached by suitable pivot bolts or rivets 19 to the side bars 16 as shown in Figure 1 so that the side bars may be readily oscillated into a position in which they are spaced from the center bar 15 a distance governed by the length of the links 17 to provide the previously referred to and herein illustrated relatively long, rectangular frame unit 14.

It will be noted that the pairs of links 17 are close to one end, that is, the upper end of the unit section so that the major portion of the center and side bars 15 and 16 are free and unconnected. These free or unconnected end portions of the bars 15 and 16 are designed to be inserted or laced in between the flexible slats 13 of the back rest in such manner as to pass across the inner side of the top rail 12 of the back rest frame and to rest upon the back rail of the spring or bottom frame, in the manner illustrated in Figure 1.

In order to maintain the attachment unit in set up position against the back rest frame, the center bar 15 is provided upon its rear side with a latching means in the form of a flexible metal strap 20 which is pivoted at 21, substantially midway between its ends, to the center bar 15. The length of the latching strap 20 is slightly greater than the distance between the two slats 13 at the center of the back rest frame.

In addition to being of a length sufficient to span the space between the two central slats 13, the latch strip 20 is pivoted to the bar 15 in the proper position to place the pivot 21 substantially midway between the two center slats 13 when the attachment is set up for use so that the latch strap 20, being upon the back of the center bar 15, may then be oscillated to a position in which it is parallel with the center bar 15 so as to bring its ends into engagement across the rear sides of the adjacent slats 13 opposite from the bar 15. Thus the attachment unit will be held against shifting movement upon the base or spring frame of the swing structure and when the back cushions, not shown, are set up for use against the back rest frame, an extra cushion may be placed upon the top of that cushion which is positioned in front of the attachment 14, to rest against the upper part of the attachment or, in other words, against that part which extends above the top of the swing back rest frame 11.

When the attachment is removed from the back rest frame, the side bars 16 may be oscillated through the medium of the links 17, into position in relatively close proximity to and in parallel relation with the middle bar 15 as illustrated in Figure 3, so that the device can be stored away without taking up much space.

The present device when applied to a porch swing or glider in the manner stated affords, when used, perfect relaxation, since the occupant of the glider can rest his head against the back rest supported cushion and thereby relax the tension of the muscles normally required to maintain the head in an upright position.

I claim:

1. The combination with a porch swing or glider having a back rest frame against which back rest cushions are positioned and including horizontal, vertically spaced slats, of a relatively long auxiliary frame unit including spaced parallel bars adapted to be disposed vertically in

the use of the attachment, said bars being laced between the back rest slats and said attachment being of such length as to extend a substantial distance above the top of the back rest frame to provide an auxiliary cushion supporting means.

2. The combination with a porch swing or glider having a seat frame and a back rest frame, in which the back rest frame includes vertically spaced, horizontal slats, of an auxiliary cushion supporting means comprising a plurality of relatively long parallel bars having their ends laced between the back rest slats and supported upon the seat frame to extend upwardly above the top of the back rest frame, means connecting upper ends of said bars above the back rest frame, and means carried by one of the bars for locking the auxiliary supporting means to the back rest frame.

3. The combination with the back rest frame of a porch swing or glider having horizontal, vertically spaced slats of a plurality of flat bars disposed in parallel relation and having a length materially greater than the height of the swing back rest frame, link members pivotally joining said bars together at one end only to facilitate moving the bars relatively one to the other whereby such bars may be separated and brought into close parallel relation as desired and whereby the bars at their other ends may be laced between said back rest frame slats, and means carried by one of the bars for establishing a locking connection between the same and a part of said back rest frame.

GERARD ANGELOT.
